Primary Examiner — T Chase Nelson(74) *Attorney, Agent, or Firm* — Quarles & Brady LLP(57) **CLAIM**

The ornamental design for a shoe, as shown and described.

DESCRIPTION

FIG. 1 is a top, left, front perspective view of the shoe showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Any broken lines in the drawings indicate portions which form no part of the claimed design. The dark shading represents a contrast in appearance only and does not represent any particular color, material, texture, or finish.
